UNITED STATES PATENT OFFICE

154,654

DESIGN FOR A PREMATURE INCUBATOR

Samuel M. Behar, Glendale, Calif., assignor to
E. & J. Manufacturing Co., Glendale, Calif., a
corporation of California

Application December 8, 1947, Serial No. 143,018

Term of patent 14 years

(Cl. D83—1)

To all whom it may concern:

Be it known that I, Samuel M. Behar, a citizen of the United States, residing in Glendale, in the county of Los Angeles and State of California, have invented a new, original, and ornamental Design for a Premature Incubator, of which the following is a specification, reference being had to the accompanying drawings, forming a part thereof.

Figure 1 is a top plan view of a premature incubator showing my new design.

Figure 2 is a front elevational view of my premature incubator;

Figure 3 is a rear elevational view thereof;

Figure 4 is an elevational view of one side thereof.

Figure 5 is an elevational view of the other side thereof.

I claim:

The ornamental design for a premature incubator, as shown.

SAMUEL M. BEHAR.
